UNITED STATES PATENT OFFICE

2,272,675

CENTRIFUGAL SEPARATOR

George M. Knudsen, Redlands, Calif.

Application March 11, 1940, Serial No. 323,331

6 Claims. (Cl. 233—27)

This invention relates to improvement in centrifugal separators.

The general object of this invention is to provide an improved centrifugal separator particularly adapted for use in separating mineral from gravel or ore.

Another object of the invention is to provide a centrifugal separator that is resistant to wear and has high efficiency.

A further object of the invention is to provide a separator that is easily, quickly and completely cleaned.

An additional object of my invention is to provide a centrifugal separator bowl which is made of non-magnetizing material.

Another object of the invention is to provide a rubber riffle member for a centrifugal separator.

A still further object is to provide a novel liner for a centrifugal separator which is easily cleaned and easily removed.

Other objects and the advantages of this invention will be apparent from the following description taken in connection with the accompanying drawing, wherein:

Fig. 1 is a central vertical section through my improved centrifugal separator;

Fig. 2 is a plan view of my improved separator; and

Fig. 3 is an enlarged, fragmentary section taken on line 3—3, Fig. 2.

Referring to the drawing by reference characters I have indicated my improved separator generally at 10. As shown the separator 10 includes a hemispherical bowl 12 preferably made of aluminum or other non-magnetizing material. The bowl 12 includes an annular rim 13 and a hub 14. A bore 15 extends through the hub 14. The axes of this bore 15 and the hub 14 may be slightly offset from the axis of the bowl in order to produce a wobble action when the bowl is rotated.

A rubber bowl shaped riffle member 16 is loosely positioned within the bowl 12 and includes an upper rim 17 which extends outwardly and overlies the bowl rim 13. The riffle rim also extends inwardly as at 18. A plurality of annular ribs 19 are shown as formed integral with the riffle member 16. As shown in Fig. 3 each rib 19 extends inwardly the lower surface 20 thereof being substantially horizontal and the upper surface 21 thereof inclined slightly downwardly.

The riffle member 16 has a central aperture 22 at its lowest point. The member 16 is clamped

between the inner surface of the bowl 12 and a metal plate 23 by a plurality of bolts 24. The riffle member is attached only at the bottom, the side thereof and the edge being free to shift slightly in the bowl.

The bolts 24 also secure the hub 14 to a flange 25 secured to a hollow output shaft 26 of a gear box 27. The upper end of the shaft 26 is positioned in the bore 15. The aperture 22 is in alignment with the bore of the hollow shaft 26. A flange 28 secured to the gear box 27 is secured to a suitable support 29 by bolts 30. A suitable stopper or plug 26' is preferably positioned within the upper end of the hollow shaft 26 and within the bowl 12.

An input shaft 31 of the gear box 27 extends at right angles to the shaft 26 and has a drive pulley 32 secured thereto.

A circular launder 33 is coaxially positioned about the rim 13 of the bowl 12. The launder 33 includes an outer cylindrical rim 34, an inner cylindrical rim 35 a flat inclined bottom 36 thus forming an asymmetrical annular chamber. A circular discharge chute 37 is provided adjacent the lower portion of the bottom 36. The rims, bottom and chute are suitably secured as by welding to form a unit.

The launder 33 is shown as supported by a plurality of angle iron legs 38 suitably secured to the outer rim 34 as by welding. The legs 38 extend downwardly and terminate at bearing plates 39 which are secured to the support 29 by bolts 40.

An overflow guard 41 is provided and comprises a cylindrical portion 42 and an annular portion 43 suitably secured thereto as by welding.

The guard 41 is held suspended in position in the launder 33 by a plurality of plates 44 the ends of which engage the upper edge of the portion 33 and which are shown as adjustably secured to the disk portion 43 by bolts 45 and washers 46. Elongated slots 47 are provided in the plates 44 to permit adjustment.

A deflecting baffle blade 48 is secured to each of the plates 44 and extends downwardly parallel to the sides of the bowl 12. It will be seen that the overflow guard and baffle blade assembly form a removable unit normally engaging the launder.

In operation a suitable quantity of ore is introduced into the riffle member 16 preferably in a finely divided state and when desired mixed with sufficient water to form a pulp. The bowl 12 and the riffle member 16 are then rotated by

a suitable prime mover (not shown) through the pulley 32 and the gear box 27.

Free metallic particles, such as gold, are carried by centrifugal action into the spaces between the ribs 19 and the waste material passes upwardly and is discharged into the launder 36 whence it is discharged through the chute 37. The separating action is aided by the agitation resulting from the wabbling action of the bowl 12 and by the kneading action of the soft flexible rubber ribs of the riffle member. The baffle blades 44 prevent any scouring action which might otherwise remove the separated metal from between the ribs of the riffle member. The bowl may be cleaned by removing the plug 26' and flushing with water.

By making the bowl of non-magnetizing material I secure an improved result, since with an iron or steel bowl a magnetic field appears to be set up by the rotation of the separator and this field appears to magnetize the magnetic iron (or magnetite) which frequently occurs in placer sands, thus causing the iron containing particles to adhere and pack in an iron or steel bowl.

By providing the wabbling action of the bowl I secure a better result, due apparently, to the varying pressure from the centrifugal action of the material on the flexible rubber riffing. This action appears to provide a sort of kneading movement so that a better recovery is made.

From the foregoing description it will be apparent that I have invented a novel centrifugal separator which is highly efficient for its intended purpose.

Having thus described my invention, I claim:

1. In a centrifugal separator, a base, a vertical shaft rotatably mounted on said base, means to rotate said shaft, a bowl member mounted on said shaft for a wabbling rotation, a flexible resilient riffle member positioned within and conforming to said bowl member and centrally secured thereto, said riffle member including a plurality of inner annular flexible ribs, the lower surface of said ribs being substantially horizontal and the upper surface thereof inclined, an annular trough-like launder surrounding the periphery of said bowl, and an over-flow guard ring engaging the top of said launder.

2. In a centrifugal separator, a base, a vertical shaft rotatably mounted on said base, means to rotate said shaft, a substantially hemispherical bowl member mounted on the upper end of said shaft with the axis of said shaft out of alignment with the axis of said bowl to provide a wabbling rotation of the bowl, a flexible resilient riffle member positioned within and conforming to said bowl member and centrally secured thereto, said riffle member including a plurality of inner annular flexible ribs, the lower surface of said ribs being substantially horizontal and the upper surface thereof inclined, an annular trough-like launder surrounding the periphery of said bowl, said launder including an inclined bottom and a chute adjacent the lowest point of said bottom, an over-flow guard ring engaging

the top of said launder, and radial baffle plates adjustably secured to said ring, said baffle plates extending into the bowl.

3. In a centrifugal separator, a base, a vertical hollow shaft rotatably mounted on said base, means to rotate said shaft, a removable plug in the lower end of said hollow shaft, a substantially hemi-spherical bowl member mounted on the upper end of said hollow shaft with the axis of said shaft slightly eccentric to the axis of said bowl, a flexible, resilient, riffle member positioned within and conforming to said bowl member and centrally secured thereto, said hollow shaft communicating with the interior of said riffle member, said riffle member including a plurality of inner annular flexible ribs, the lower surface of said ribs being substantially horizontal and the upper surface thereof inclined, an annular trough-like launder surrounding the periphery of said bowl, said launder including an inclined bottom and a chute adjacent the lowest point of said bottom, an over-flow guard ring engaging the top of said launder, and a plurality of radial baffle plates adjustably secured to said ring, said baffle plates conforming to the shape of the riffle member and spaced therefrom.

4. In a centrifugal separator, a base, a vertical shaft mounted to rotate on the base, a one piece bowl made of nonmagnetizable material, means to eccentrically mount the bowl on the vertical shaft, and a flexible rubber riffle lining member within said bowl, said member having the upper portion thereof free from attachment to the bowl, said member including a plurality of inner, annular, flexible ribs, said ribs having horizontal bottoms and having downwardly and inwardly inclined upper surfaces.

5. In a centrifugal separator, a hollow shaft, a substantially hemispherical bowl member mounted on and communicating with said hollow shaft, a riffle member within said bowl member and conforming thereto, said riffle member including a plurality of flexible inner annular ribs, and means adjacent to the axis of the bowl for securing the riffle member to the bowl, the riffle member being elsewhere free from attachment to the bowl.

6. In a centrifugal separator, a base, a vertical shaft rotatably mounted on said base, means to rotate said shaft, a substantially hemi-spherical rubber bowl member mounted on said shaft, a flexible resilient riffle member positioned within and conforming to said bowl member and centrally secured thereto, said riffle member extending loosely over the interior of said bowl member, said riffle member including a plurality of inner annular flexible ribs, the lower surface of said ribs being substantially horizontal and the upper surface thereof inclined, an annular trough-like launder surrounding the periphery of said bowl, an overflow guard ring engaging the top of said launder and planar radial baffles removably secured to said ring and extending into the bowl.

GEORGE M. KNUDSEN.
